UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

TRACK FOR SLIDING DOORS.

Application filed July 28, 1921. Serial No. 488,257.

To all whom it may concern:

Be it known that I, STUART W. PARSONS, a citizen of the United States, and a resident of New Britain, county of Hartford, 5 State of Connecticut, have invented certain new and useful Improvements in a Track for Sliding Doors, of which the following is a specification.

This invention relates to tracks for sliding doors such as is used in garages and other buildings. As an instance of a use to which a track of the present invention may be applied reference may be had to a sliding door arrangement wherein the doors 10 are hinged together and are adapted to be rolled from the garage entrance around a bend to the side walls of the garage. The aim of the invention is to provide a track of this sort made up of a 15 plurality of relatively short sections and having simple and economical means for readily and securely connecting the sections together in correct alinement.

In the accompanying drawings, 25 Fig. 1 is a general view showing a track constructed with one embodiment of the present invention and doors suspended on this track,

Fig. 2 is a view on a larger scale of the 30 joint between the track sections,

Fig. 3 is a sectional view taken on line 3—3 of Fig. 2,

Fig. 4 is a view in perspective of a joint 35 constructed in accordance with another embodiment of the present invention, and

Fig. 5 is a sectional view taken on line 5—5 of Fig. 4.

Referring to the drawings in detail, *a*, *a*, 40 denote the doors, connected by hinges *b* and suspended by hangers *c* from a track *d*, connected by brackets *e* to the walls of the building or garage.

In accordance with the present invention, 45 the track *d* is made up of a plurality of relatively short sections 10, 10, each section preferably comprising a flat strip of metal. The abutting ends of contiguous sections have interfitting tongues 11 and recesses 12. Each section adjacent each end is provided 50 with an aperture 13 and at one end with an additional aperture 14. The numeral 16 denotes a joint plate overlapping the abutting ends of the sections and having apertures similar to and registering with the 55 respective apertures 14, 13. The brackets *e*

are preferably formed of metal strips bent to the shape shown. The vertical arms of these brackets may be provided with openings 17 to receive the screws employed for securing the brackets to the wall of the 60 garage or other building.

The horizontal arms of these brackets terminate in a pair of spaced lugs 18, 19, which extend through the apertures in the plate 16 and into the apertures 13 in the track sections. The end of the lug 19 extends beyond one of the track sections 10 and is headed over as shown so as to permanently secure together the bracket, the plate 16 and this track section. The other lug 18 tapers down 70 slightly towards its end so as to wedgedly fit within the aperture 13 in the other track section. This other track section and the plate 16 are connected together by suitable securing means which, in the present instance, is in the form of a bolt 21 which extends through the aperture 14.

It will be noted that with the arrangement described, all of the parts making up the track, excepting of course the bolt 21, 80 may be constructed from flat strips or sheets of metal thus providing a structure which may be very economically manufactured. The brackets employed for securing the track to the building walls are also used in 85 connecting the track sections together. Since the track comprises a plurality of relatively short sections the track may be compactly packaged and sold in a single bundle along with the hinges, hangers and other articles necessary to make up a complete set. A person may buy any length of track he desires and then arrange the sections to the best advantage on the garage walls.

With the arrangement described the track 95 sections may be very readily and quickly joined and the track set up on the wall of the garage by any unskilled person. The sections are joined together in such manner that they necessarily must be in correct 100 alinement.

It will be seen that after the parts are brought together, and when the bolt 21 is tightened up, the tapered lug 18 will bring the track sections into correct alinement. 105 The sections are very securely connected together so that they will not sag and their alinement will not be disturbed by the weight of the door.

Referring now to the embodiment shown 110

in Figs. 4 and 5, wherein the same advantages are obtained as in the structure shown in the preceding embodiment, the bracket e' is provided with a pair of tapered studs 18' which take into apertures 13 in the track sections 10. The plate 16' is connected at its opposite ends by bolts 21 to the respective sections 10, and this plate is bowed out at its central portion and is recessed at its lower edge as at 25. In the opposite edges of the bracket e' are notches 26 into which the side edges of the recess 25 of the plate are adapted to fit. It will be readily understood that to secure the parts together the track sections are brought end to end and the lugs 18' of the bracket are then inserted into the opening 13. The plate 16' is then lowered on to the bracket so that the recess 25 receives the neck between the notches 26 of the bracket and then the bolts 21 are inserted and tightened up.

It is of course obvious that my invention is susceptible of various modifications and changes which are within the spirit of the invention without departing from the scope of the following claims, it being understood that the present disclosure is by way of illustration only and it is not to be taken as restrictive of my conception.

30 I claim as my invention:—

1. In a device of the character described, track sections positioned end to end, a bracket having lugs extending through the respective sections, and a plate formed separately from said bracket and overlapping and secured to the abutting ends of said sections, said plate and bracket being in engagement with one another whereby one secures the other in position.

40 2. In a device of the character described, track sections positioned end to end, a sheet metal bracket member having portions extending into the respective sections, and a sheet metal plate member overlapping and secured to the abutting ends of said sections, one of said members having a portion interposed and clamped between the other member and one of said track sections.

3. In a device of the character described, track sections each having an aperture adjacent its abutting end, a right angle bracket formed from sheet metal and having one arm terminating in a pair of spaced integral lugs respectively engaging in said apertures, and a plate secured to said sections and having interlocking engagement with said bracket.

4. In a device of the character described, track sections positioned end to end and each having an aperture adjacent its abutting end, a bracket having a pair of lugs engaging in said respective apertures, and a

plate cooperatively connected with said bracket and secured to said sections.

5. In a device of the character described, 65 track sections each having an aperture adjacent its abutting end, a bracket having a pair of lugs respectively engaging in said apertures, a plate engaging said bracket, and means apart from said bracket for detachably connecting said plate to one of said sections. 70

6. In a device of the character described, a plurality of units each comprising a track section, a plate member overlapping one end thereof and secured thereto, and a bracket formed separately from said plate and provided with means for securing said plate to said section. 75

7. In a device of the character described, 80 a plurality of units each including a track section having an aperture adjacent one end, a plate member overlapping one end of said section, and a bracket having a lug extending through said plate and the aperture in 85 said section, said lug being headed to secure the parts together.

8. In a device of the character described, 90 a plurality of units each including a track section having an aperture adjacent one end, a plate member overlapping one end of said section, and a bracket having a pair of lugs, one lug extending through said plate and aperture and headed to secure the parts together, and the other lug extending through said plate and adapted to be received by an aperture in the end of an adjacent section. 95

9. In a device of the character described, 100 track sections each having an aperture adjacent its adjacent end, a bracket having a pair of lugs respectively engaging in said apertures, a plate cooperatively connected to said bracket, and a bolt for securing said plate to one of said sections.

10. In a device of the character described, 105 track sections each having an aperture adjacent its abutting end, a plate overlapping said abutting ends and having apertures corresponding to and registering with the apertures therein, a bracket having lugs extending through the apertures in said plate and sections, one of said lugs being headed to secure said bracket and plate to one of said sections, and means for securing said plate to the other section. 110

11. In a device of the character described, 115 track sections each having an aperture adjacent its abutting end, a bracket having a pair of lugs respectively engaging in said apertures, one of said lugs being tapered and wedgedly fitting in one of said apertures, and means for securing the parts together. 120

STUART W. PARSONS.
